PACKAGING TRAY

Gilbert R. Chadbourne, Oakland, Maine, assignor to Keyes Fibre Company, Portland, Maine, a corporation of Maine

Filed Jan. 10, 1964, Ser. No. 78,146

Term of patent 14 years

(Cl. D58—13)

Fig. 1

Fig. 3

Fig. 4.

Fig. 5

FIG. 1 is a top plan view of a packaging tray, showing my new design;

FIG. 2 is a side elevational view thereof;

FIG. 3 is an end elevational view thereof;

FIG. 4 is a sectional elevational view on line 4-4 of FIG. 1; and

FIG. 5 is a fragmentary bottom plan view thereof.

I claim:

The ornamental design for a packaging tray, as shown.
